CLAIM

The ornamental design for a dust collecting device for nail care, as shown and described.

DESCRIPTION

FIG. 1 is a perspective view of a dust collecting device for nail care, showing my new design, wherein the details shown in the broken lines are for illustrative purposes only and form no part of the claimed design;

FIG. 2 is a back view of the dust collecting device for nail care, wherein the details shown in the broken lines are for illustrative purposes only and form no part of the claimed design;

FIG. 3 is a front view of the dust collecting device for nail care, wherein the details shown in the broken lines are for illustrative purposes only and form no part of the claimed design;

FIG. 4 is a left view of the dust collecting device for nail care, wherein the details shown in the broken lines are for illustrative purposes only and form no part of the claimed design;

FIG. 5 is a right view of the dust collecting device for nail care, wherein the details shown in the broken lines are for illustrative purposes only and form no part of the claimed design;

FIG. 6 is a top view of the dust collecting device for nail care; and,

FIG. 7 is a bottom view of the dust collecting device for nail care, wherein the details shown in the broken lines are for illustrative purposes only and form no part of the claimed design.
